(57) **CLAIM**

The ornamental design for a drawer slide panel as shown and described.

DESCRIPTION

FIG. 1 is a front, left and top perspective view of a drawer slide panel, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the drawer slide panel in a usable state.

The broken lines in the drawings illustrate portions of the article that form no part of the claimed design.
